YARN INSPECTING DEVICE

Edward O. Jennings, Philadelphia, Pa.

Application April 16, 1935, Serial No. 16,606

1 Claim. (Cl. 28—26)

My invention relates to a new and useful yarn inspecting device and it relates more particularly to a device whereby a plurality of yarns may be inspected simultaneously with a great saving of time and effort.

In the manufacture of yarns it is necessary that each lot produced should be inspected and graded or calibrated, so that when the yarn is sold for the manufacture of finished goods, the character of the goods produced (except for defects occurring during the weaving or knitting thereof) can be predetermined. Thus if the yarn used is not inspected beforehand, it is necessary to inspect and sort the finished goods into "firsts" and "seconds" or some similar gradation. If however, the yarn is inspected and graded beforehand, the finished goods produced can be graded as "firsts" or "seconds" according to the grade of the yarns used in the manufacture thereof. In the inspection of yarns, it has been found that if a few yards from a given cone are inspected, it is safe to assume that the rest of the cone would probably average the same number of defects per yard, if any, as appeared in the few yards inspected, and by inspecting a few yards from a few cones belonging to one lot of manufactured yarns, it is possible to estimate within practical limits the general condition of the whole lot of yarn, without the necessity of inspecting each and every cone of the yarn produced. For example, if a lot of yarn is produced and wound on one hundred cones and a few yards are inspected, of say, each of twenty cones picked at random, it is safe to assume that the yarn on all the one hundred cones is approximately the same calibre as the specimens inspected. In this way the manufacturer can represent all the one hundred cones as being of a particular grade depending on the number of defects per yard occurring in the yarn specimens from a number of cones, picked at random from the lot of yarn in question.

It is therefore the object of my invention to produce a novel inspecting device which is inexpensive to make and easy to operate, and on which yarn specimens from a number of cones can be inspected simultaneously and in very short order.

To the above ends my invention consists of a large drum of a known circumference on which the yarn specimens may be wound, means for rotating said drum, a feed screw shaft rotating synchronously with said drum for feeding the yarn specimens onto the drum and means for permitting the simultaneous winding on said drum of

yarn specimens from a number of different cones.

My invention further consists of various other details of construction and advantage all as hereinafter set forth in connection with the accompanying drawing, in which:—

Fig. 1 represents an end elevation of a yarn inspecting device embodying my invention.

Fig. 2 represents, on an enlarged scale, a front elevation of Fig. 1.

Fig. 3 represents a plan view of Fig. 2.

Fig. 4 represents, on a slightly enlarged scale, a section on line 4—4 of Fig. 2.

Fig. 5 represents a front elevation of the half-nut feeding device seen at the upper half of Fig. 4, shown detached.

Referring to the drawing in which like reference characters indicate like parts; 1 indicates any suitable frame or housing in the upper portion of which is suitably rotatably mounted the drum 2. The drum is driven by the belt 3 which travels over the pulley 4 on the shaft 5, driven by the motor 6 and over the pulley 8 carried by or otherwise associated with the drum 2. The shaft supporting the drum 2 is also provided with the pulley 10, over which travels the belt 11 which also engages the pulley 12 to rotate the feed screw 14 which is journalled in the bearings 15 and which rotates in the semi-cylindrical casing 16, which may contain a lubricant, if desired. In order to vary the speed, if so desired, the extra pulleys 17 and 18 are also provided. 20 represents a feed half-nut, the threaded part 21 of which is adapted for engagement with the upper threaded half of the feed screw 14, while the legs 22 of which are adapted to ride on the upper edges 23 of the semi-cylindrical trough or casing 16. The feed half-nut is provided on a face thereof with the posts or screws 25, 26 and 27 over, around and under which the yarn to be inspected may be threaded to accomplish the desired tension.

The operation is as follows:—If it is desired to inspect the yarn 30 from the cone 31 and the yarn 32 from the cone 33, it is merely necessary to position the cones on the floor or on a platform in front of the machine, and to thread the yarns 30 and 32 thereof through the eyelets 34 and 35, the yarns being then passed over, around or under any or all of the posts or screws 25, 26 and 27 in the manner shown in Fig. 1 or in any other desired manner, depending on the amount of tension desired, which in turn depends on the speed of rotation of the drum, as well as on the character of the yarn. The free ends of the yarns 30 and 32 are tied or otherwise anchored

to the posts 38 and 39, whereupon the switch controlling the motor 6 is turned on and the drum is rotated at a set speed. This results in winding over the drum any desired length of yarn from the cones 31 and 33 as shown in Fig. 2. The motor 6 is then turned off and by depression of the brake lever 40, which is tensioned by the spring 42, the brake shoe 45 acts to stop the rotation of the drum 2. The yarn thus wound around the drum is then inspected for defects and the defects are averaged with respect to the number of yards of the yarn wound on the drum, which is determined by the number of times the yarn is wound around the drum, multiplied by the known circumference of the drum. Thus, if the circumference of the drum is 6 ft. and if an average of 2 defects are found for each turn of the yarn around the drum, it will be seen that this particular yarn averages a defect per yard and the yarn is thus correspondingly graded. The drum is painted in a color which will contrast with the color of the yarn to be inspected, to facilitate vision and accuracy in inspection. In order to facilitate the removal of the yarn wound around the drum after it has been inspected, the drum is provided with one or more longitudinal slots 48 so that a knife may be passed over the yarn and through the slot, thus cutting the continuous turns of yarn into small sections which can be easily removed from the drum. The feed half nut 20 riding on the upper edges 23 of the semi-cylindrical casing 16 and engaging the feed screw 14, travels in the direction of the lead of the thread of the feed screw, which is driven synchronously with the drum, thus uniformly feeding the yarn onto the drum. While in the drawing I have illustrated the inspection of yarn from only two cones, it is to be understood that in practice the number of cones, the yarns of which may be inspected simultaneously, is limited only by the length of the drum 2 and the feed screw 14; since with a drum of 6 ft. in circumference, it would only be necessary to have from 2 to 4 or 5 turns of yarn around the drum to obtain a representative specimen of the yarn on any particular cone, so that the yarn from quite a number of cones can be

tested simultaneously on a drum 4 ft. long. It is of course understood, that after the yarn from one set of cones has been tested, the feed half nuts 20 are reset to the desired position with the first one at the extreme left hand end of the feed screw 14, and with the others spaced according to the length of yarn desired to be wound around the drum from the respective cones. When a smooth yarn having a low index of friction is being tested, it may be necessary to thread the 10 yarn around or over each one of the posts 25, 26 and 27 in order to secure the proper tension, and where a coarse yarn, having a high index of friction, is being tested, it may be found desirable to pass the yarn over only one or two 15 of the posts 25, 26 and 27.

It will thus be seen that with my novel yarn inspecting device, I am able to inspect one or more specimens of yarn simultaneously and in a minimum of time, since the large circumference 20 of the drum and its rapid rotation and rapid stoppage, will result in the winding on the drum, in a few seconds, of a sufficient length of yarn from each cone, to afford a basis of computation of defects in terms of a standard average. It will also be seen that the threading of the cone, in order to permit the inspection of its yarn, as well as the removal of the inspected 25 yarn from the drum, is simplified and expedited to a very great degree.

What I claim as new and desire to secure by Letters Patent is:—

A yarn inspecting device comprising, a housing, a drum of a relatively large circumference journaled in said housing, a pulley for driving 35 said drum, a reversible feed screw, a pulley for driving the same, a belt passing over both of said pulleys and adapted to be actuated by a source of power, a threaded half nut engaging said feed screw and movable longitudinally of 40 said drum, and a yarn tensioning device carried by said half nut and movable therewith, said drum having a longitudinal slot in the surface thereof and being of a color contrasting with the color of the yarn to be inspected.

EDWARD O. JENNINGS.
